SELECTIVE ARTICLE VENDING MACHINE

Kuno Edgar Hamann, Long Island City, N. Y.,
assignor to Joseph A. Lamprecht, Elizabeth,
N. J.

Application December 14, 1948, Serial No. 65,179

4 Claims. (Cl. 194—54)

1

This invention relates to improvements in vending machines and has for a principal object the provision of a machine for vending elongated articles, the cross-sections of which are round or rectangular, said machine including a plurality of main article columns, auxiliary or reserve columns for each main column, and novel means for swinging the lower end of each reserve column to the vending position as its companion main column becomes exhausted of articles.

Another object of the invention is the provision, in a vending machine, of a novel "lock-out" chain comprised of one series of lock-out members or bars, and a second series of lock-out members or bars resting upon and coextensive with the members or bars of the first series and arranged so that wedge members, each mounted on and movable with the article ejector, may enter between abutting upper and lower lock-out members of the two series, and so that when the wedge member on one of the ejector members enters between said members at one point, none of the other ejector members may be actuated.

A further object of the invention is the provision of such a lock-out chain wherein the members of both series are of the same width with the exception that the members of one of said series are each narrowed in width at one end thereof, thereby making it impossible for a person, during a vending operation wherein one ejector member is being manipulated, to pull on another ejector member to cause its wedge member to hold back the two lock-out chains so that others or the same ejector members may be operated without placing additional money in the machine. The wedge members can be held tensionally against the lock-out members which were not narrowed, but the lock-out members of the other series which are narrowed are not engaged by the wedge member and they do return to their normal positions at the end of an operation. This means that although one lock-out chain may be held against resetting, the other one cannot be prevented from resetting and therefore the machine cannot be robbed.

Another object of the invention is the provision in a vending machine, of a lock-out chain, the end member of which has movably mounted thereon, a locking bolt having a cam lug thereon adapted to cam against a coin of a predetermined value in a coin control in said machine and to be thereby shifted to an unlocked position, so that the machine can be operated.

Yet another object of the invention is the provision, in a vending machine, of a lock-out chain, the end member of which enters into and locks a coin return mechanism in said machine against operation as soon as a wedge member on one of the article ejector members enters between the abutting ends of any two lock-out members in said chain.

2

Other objects and advantages of the invention will be apparent to those skilled in the art, upon a study of this specification and the accompanying drawings.

5 Referring to the drawings, which are given by way of example to illustrate the invention:

Figure 1 is a perspective view of a vending machine cabinet, housing mechanism embodying my improvements;

10 Figure 2 is a view of the machine as seen from above, having a portion cut away to show structural details;

Figure 3 is a sectional elevation taken through one of the article columns of the machine, showing articles in the reserve column, and one article in the main column, and mechanism for shifting the bottom of the reserve column to the vending position as said one article is vended;

15 Figure 4 is a view similar to Figure 3, except that the last article is being delivered from the main column, and the reserve column has been shifted;

Figure 5 is a rear view of a portion of my vending machine, showing details of construction;

20 Figure 6 is an end elevation of the machine, showing the coin tester and scavenger, and the coin control and coin return mechanism;

Figure 7 is an elevation showing details of the coin control;

25 Figure 8 is a sectional elevation taken through the coin control and showing the path of coins therein;

Figure 9 is a sectional view taken 90° with respect to Figure 8 and showing the path of accepted coins therethrough;

30 Figure 10 is a plan view of the right end of the lock-out chain, showing a wedge member on the end ejector member entered between the adjacent ends of the lock-out members of the two lock-out chains and showing a pivoted locking member camming against a coin in the coin control to an unlocked position;

Figure 11 is similar to Figure 10, except that the ejector member has returned to its normal position and the locking member is in its locked position;

35 Figure 12 is an exploded view showing the two series of lock-out elements forming the two lock-out chains;

40 Figure 13 is a perspective view of the mechanism for shifting a reserve column to bring its lower end into vending position;

Figure 14 is a bottom view looking upwardly, and showing the article ejector members, and their follow through pawls and ratchets, and also showing the "out of stock" locks;

45 Figure 15 is a sectional elevation taken along the lines 15—15 of Figure 14 and showing the out of stock lock disabled by the presence of articles in the column;

50 Figure 16 is a view similar to Figure 15, except

that the column has no merchandise therein, consequently, the out of stock lock prevents the article ejector from being operated; and

Fig. 17 is a fragmentary cross-section of a portion of the ejecting mechanism.

Referring to Figure 1, the cabinet 20 has a door 21, hingedly mounted on the body 22 and secured in a closed position thereon by means of a lock 23. Mounted in the door 21 is a coin slot 24, and below it is a coin return button 25. Formed in the lower portion of the door 21 is an article delivery port 26. Disposed in a row above the port 26 is a series of article delivery slides 28, 29, 30 and 31 which project from a support channel 27 which forms an integral part of the mechanism, and which projects through a rectangular opening 32 in the cabinet door 21. Above the plate 27, there is formed in the door an elongated display cavity which is covered by a curved transparent closure 33 through which articles of merchandise in the several columns may be seen.

Referring to Figures 2, 3 and 4, the mechanism has a frame including vertical end plates 34, 35 which have their rear edges forming flanges 34a and 35a, respectively. Secured to the flanges, in any suitable manner, for example by means of screws 36, is a cross-member of Z cross-section 37; parallel to and spaced below the cross-member 37 is a cross-member 38 of substantially L cross-section, and this member is secured to the flanges 34a and 35a by means of screws 39. Spanning the space between the end plates 34 and 35 is a cross-member 40 having a horizontal portion 41, a depending portion 42 integral therewith, and an upstanding portion 43 formed integral with the horizontal portion 41, which joins a horizontal portion 44, which has a trough 45 formed therein extending longitudinally thereof, said trough forming a guideway for the two lock-out chains, which will presently be described.

Formed integral with the horizontal portion 44 is a depending portion 46. Secured to the portion 46 is a U-shaped channel 47 which has a downwardly extending flange 48, which is secured to the portion 46 by means of screws 49. The U-shaped channel has an upwardly extending flange 50, which forms a trim.

In Figures 3 and 4, the delivery slide 28 may be seen, and this consists of a flat rectangular plate 53 having a cylindrical grip 51 secured thereto by means of a screw 52. The inner end of the plate 53 is in the form of a downwardly directed curve 54.

Referring to Figure 14, the plate 53 has extending into it from one edge thereof, a spaced arcuate notch 55 and spaced apart therefrom is a second arcuate notch 56 and between these notches is formed a series of serrations 57. A pawl 58 is pivotally carried on a stud 59 and a spring 60 has one end secured to the pawl 58 and the other end secured to a second pawl 61 which is spaced apart therefrom and pivotally carried on a stud 62. The purpose of this pawl and the serrations 57 is as follows: When the article delivery slide is pulled outwardly to effect the delivery of an article, the pawl 58, which is normally positioned in the clearance notch 56, engages the serrations 57 and is thereby partially rotated in a counter-clockwise direction. This makes it impossible to push the slide back in until it has completed its stroke. As the slide is pulled outwardly, the pawl 58 finally reaches the clearance notch 55 and is consequently freed from the serrations 57. Now, when the slide is

returned to its normal position, the pawl is partially rotated in a clockwise direction, as it again engages the serrations 57, and the pawl is in engagement with the serrations 57 until it encounters the clearance notch 56, where it is released therefrom, and the slide remains in its normal position.

The slide 53 has an elongated slot 63 formed therein which communicates with a rectangular opening 64. Parallel to one end of the rectangular opening 64 is a depending lug or boss 65 which is tipped to accommodate a shouldered screw 66. Journaled on the shouldered screw 66 is a lever 67 which may best be seen in Figures 15 and 16.

The lever 67 has a horizontal portion 68 which has a notch 69 formed in the end thereof. The lever also has a short vertical portion 70 from which a horizontal arm 71 projects. The horizontal arm 71 works into and out of the slot 63. The extreme left end of the arm 71, as seen in Figure 16, has a downwardly extending portion 72 and this terminates in a horizontal portion 73 which is somewhat parallel to and spaced downwardly from the arm 71. A bracket 74 is secured to the lower surface of the horizontal portion 44 and this bracket has a horizontal portion 75 which is engaged by the notch 69 in the arm 68 when there is no merchandise in the column associated with the slide 53. When there is merchandise in the column associated with the slide 53, the arm 71 of the lever 67 is depressed, thereby causing the end carrying the notch 69 to rise so that the notch moves in a path above the horizontal portion 75 and thereby the slide is free to move (insofar as the lever 67 is concerned), when merchandise is in position in the column with which the slide is associated.

A stud 76 has a shank 77 of reduced diameter which extends through a hole formed in the slide 53 so that the body part 76 extends downwardly. Positioned on the shank portion 77 and bearing against the upper surface of the slide 53 is an interposer member 78 which has an angular camming surface 79. The interposer is secured on the slide 53 by means of a nut 80 threadedly engaging the shank 77. The interposer has an upturned tail 81, the function of which will be presently described. This interposer may be clearly seen in the plan views (Figs. 10 and 11).

It will be noted in Figures 15 and 16 that the interposer 78 is comprised of two separate pieces, one on top of the other. The function of the interposers is for them to cam themselves in between abutting elements of a lock-out chain. In the embodiment shown in the drawings, I employ two lock-out chains, one superimposed on the other, and I would like to point out that although the shapes of the two pieces comprising each interposer are identical, they may be made in other shapes not identical with each other, in which instance the shapes of the camming surfaces of the elements of the lock-out chain would be suitably shaped to cooperate with them.

Since all of the article ejector slides are substantially identical, it is believed that the description of the slide 53 will suffice for all of them, making it unnecessary to repeat this description three additional times to cover the four article delivery slides 28, 29, 30 and 31.

Extending across the machine beneath all the article delivery slides 28, 29, 30 and 31, is a bar 82 which has downward extensions 83 and 84 which are pivotally connected to the end plates 34 and 35, respectively, one such connection being

shown at 85, Figure 4. In each end plate adjacent to the ends of the bar 82 are formed rectangular clearance holes such as that shown at 86. Spaced apart from and at a higher level in said end plates are formed elongated holes, such as the hole 87.

Extending across the machine and extending through the hole 87 in each end plate is a rod 88, one end of which has a connecting rod 89 pivotally connected thereto at 90, Figure 14. The other end of this connecting rod has a screw 91 extending therethrough and engaging the end 84 of the bar 82 via the hole 86. A spring 92 is secured to the screw 91 and to the depending portion 42 of the frame member 40, and urges both the bar 82 and the rod rearwardly in the machine. The other end of the rod 88 has a connecting rod 93 connected thereto at 94, and this connecting rod is connected to the other end 83 of the bar 82 via the hole 86 with a screw 95 and a spring 96 has one end connected to the screw 95 and to the frame member 41 so that this spring also urges the bar and the rod rearwardly.

In Figures 3, 4, 14, 15 and 16, it will be noted that when any one of the article ejectors 28 to 31 is pulled out, the depending stud, such as the stud 76, engages the bar 82 and moves it forward as the ejector slide moves forward. This causes the bar 88 to move forward also with the following result:

Referring to Figure 3, as the ejector slide 28 is pulled to the left, it is moved from under the lowest article 97, allowing said article to move down and come to rest on the web 41 of the cross member 40. By this time the rod 88, due to its interconnection with the bar 82, is positioned at the left ends of the aligned slots 87, so the article 97 is between the right end of the ejector 28 and the rod 88. Now, as soon as the ejector starts to return to its normal position (to the right) the article and the rod 88 move therewith until a point is reached where the article passes beyond the right edge of the support 41 and passes via the passage 100, formed between the curved wall 98 and the baffle 99, to the delivery opening 26 (Figure 1). As the article 97 is being moved to the right as described, and passes out from under the next succeeding article, the latter moves down and rests upon the upper surface of the article delivery slide 28.

In connection with Figure 3, it will be noted that the articles are carried in a column 102 having two article passages 101 and 103 therein. The article 97 is the last one in the passage 101. Now since a spring 105 urges the bottom of the column outwardly, the column being pivoted on the frame at 106, an arm 107 of a bell crank 108, forming part of mechanism which has the column locked in the position shown in Figure 3, is uncovered so that the bell crank is free to swing up to the position shown in Figure 3. This allows the trip mechanism to trip on the next operation (which is the operation described above) so that the lower end of the column 102 swings to the left to bring the lower end of passage 103 into vending position. This means that as article 97 is delivered, the column swings outwardly, and the article 104 is the next one to arrive on the upper surface of the ejector plate 28. A description of the trip mechanism will be hereinafter made in connection with Figures 2 and 13.

Referring now to Figures 2 and 10 to 13 inclusive, the lockout chain is disposed in a lon-

gitudinal troughway 45 and includes free slideable elements 110, 111, 112, 113 and 114 which abut each other endwise. These elements are all identical except the element 114. Each has its rear edge notched out from the right end as seen in Figure 12 and each notch is designated by the numeral 115, and each, with the exception of element 110, has a beveled end 116 formed thereon. The element 114 has a threaded hole 117 formed therein.

Beneath these lockout elements are a second series of lockout elements 118, 119, 120, 121 and 122, the lengths which are identical with the elements of the first series, except that the element 122 is longer than the element 114. Each upper element is positioned on a lower element and the abutting ends of all of them are coincident so that when an article ejector slide is pulled, the interposer 78 thereon enters between both the abutting ends of two lower elements and the abutting ends of two upper elements.

The left ends of all of the lower elements except the end element 118 have bevels 123 formed thereon which coincide with the bevels 116 of the upper elements.

The element 122 has a stop pin 124 extending downwardly therefrom. A barrier 125 at the left end of the chain consists of a horizontal body 126 having a hole 127 therein and has an upturned end 128 against which the left ends of the elements 110 and 113 abut. The element 125 is secured in the troughway by means of a screw passing through the hole 127. The purpose of the notches 115 is to prevent a dishonest person from cheating by pulling a second ejector slide to force the interposer thereon against any of said elements, while another ejector slide is in an outward position, and preventing them from returning to their normal positions when said first ejector slide is returned to its normal position. This is impossible because, even though bottom elements may be engaged and held by the interposers, the upper ones, due to the notches 115, within the range of the interposers, which prevent the engagement of said interposers with the edges of the upper elements, therefore, the latter cannot be held against movement.

Mounted on the outer surface of the end plate 34, Figure 6, is a coin control 130, and mounted above it and communicating therewith is a scavenger and coin tester 129, which is a purchased device. Secured on the end plate 34 is a block 131 having a lug 132 thereon engaged by a shoudered screw 133, Figure 6. Journaled on this screw is a bell crank 134, one arm of which is pivotally connected to a rod 135 extending down from the scavenger. The other arm has an elongated slot 136 therein which engages a stud 137 carried by a coin return bar 138. A pin 139 in this bar limits its forward movement, and the bar is urged forwardly by a spring 140 engaging an ear 142 on the bar and a post 141 on the control. The bar 138 has a rectangular slot 143 formed therein which is normally in alignment with the end of the lower lockout chain element 122 so that as a purchaser pulls an ejector slide forward, the interposer 78 thereon enters the lock out chain and the end elements 114 and 122 of the respective series of lock out elements are moved endwise. What happens when 114 is moved will be presently described. However, the end of the element 122 enters the slot 143 formed in the coin return bar 138 and prevents the purchaser from operating the coin return bar.

If the purchaser wants his money back before a delivery cycle of the machine is started, he may press the coin return button 25, thereby moving the bar 138 rearwardly against the urge of the spring 140. This opens the scavenger, and at the same time a lug 144 on the bar 138 acts against a lug 145 on a gate member 146, thereby releasing the coin 147 and allowing it to roll down the incline 149, like 147a, and into the coin return chute 148. The gate member is hinged at 150 and is urged to its normal position by spring means within its hinge joints, Figs. 6 and 7.

Coins enter the control via a passage 151, Figure 8, between plates 152 and 153, and the first coin comes to rest on a tab 154 formed on a lever 155 which is hinged at 156 and urged to its normal position by a spring 157.

A lever 158, hinged at 159 on the plate 152, has a tab 161 on its lower end which may extend through a hole 160 in the plate 152 and contacts the plate 153, thereby preventing other coins (where several are inserted) from passing into the accepted coin receptacle. This lever is urged inwardly by a spring 162, Figure 9, and moves in unison with the lever 155 due to the fact that the tab 155a extending between them is always in contact with the lever 155.

Referring to Figures 10 and 11, the lockout element 114 has a shouldered screw 163 engaging the threaded hole 117 (Figure 12) and journaled on this stud is a lever 164 which has a tail 165 with an upturned tab 166 thereon. One end of a hairpin spring 167 extends through a hole in said tab, and the spring is secured to a support 53 by means of a screw 168 so that the spring 35 urges the lever in a counter-clockwise direction, as seen in Figures 10 and 11. The lever 164 has a lateral extension 169 thereon having an angular cam surface 170 formed thereon. The end 171 has a notch 172 formed thereon. This end extends through a rectangular hole 173 in a fixed frame member 174, and the notch 172 engages the solid portion 174a of the frame member adjacent to one end of the rectangular hole 173, and thus the machine is locked up so that no interposer can enter the lockout chain.

Figure 10 shows the relative position of a coin 147 in a position to unlock the machine. This is the position shown in Figure 7 suitably supported by elements described in connection with Figures 6, 7, 8 and 9. The interposer has started to enter the lockout chain and the cam surface 170 on the lever has cammed against the edge of the coin 147 and has caused the lever 164 to move in a clockwise direction as seen in Figure 10, thereby disengaging notch 172 from the solid portion 174a at the end of the hole 173 and allowing the end 171, 172 of the lever to pass through the hole 173. A pin 175 on the lever 164 engages the lever 155, when it has moved sufficiently to contact lever 155, displacing the same and allowing the coin to pass into an "accepted" receptacle. At the same time the interposer 78 may freely enter the lockout chain as the slide ejector is manipulated to effect the delivery of a desired article.

The bell crank 108 (Figures 2, 3, 4 and 13) has in addition to the arm 107, an arm 176 which has a cross extension 177 on its outer end. This bell crank is journaled on a stud shaft 178 carried in a bracket 179 on the column 102. An angle member 180, Figure 13, of which the bracket is an integral part, is secured on the article column with its edge 181 flush with the lower end of the column.

A U shaped channel 182 having legs 183 and

184 has hooks 185 and 186 formed on the ends thereof. This channel is journaled on a shaft 187 and is urged upwardly by a spring 188, and its upward limit of movement is defined by fixed lugs 189 and 190. The legs 183 and 184 have concave curved upper surfaces 191 and 192. Fixed triangular members have edges 193 and 194 forming stops to be engaged by the edge 181 on the article column 102 when it is released.

In Figure 3, the column 102 is shown with its angle edge 181 engaged by the hooks on the ends of the U shaped member and retained in a vertical position. When the front section 101 of the column has more than one article in it, the arm 107 of the bell crank is held in a vertically downward position by the articles, and when this is the case, the cross member 177 is held up above the path traversed by the tail 81 on the interposer. However, when only one article is left in the section 101, the arm 107 is free to swing upwardly and the cross end 177 moves downwardly until it contacts the concave surfaces 191 and 192. After this occurs, the next time the article ejector is pulled outwardly, the cross member 177 ratchets over the tail 81 on the interposer so that when the ejector moves inwardly again, the tail 81 engages the cross-member 177, causing it to move downwardly and along the concave surfaces. This forces the legs 183 and 184 downwardly, releasing the bottom of the column 102 to swing outwardly under the urge of spring 105 until arrested by the engagement of the edge 181 with the stop edges 193 and 194, thereby positioning the section 103 for delivering articles therefrom. This position is shown in Figure 4.

For vending articles which are cylindrical in form, reference is made to the modification in Figure 17, wherein a shaft 196 is journaled in both the end plates 34 and 35 and is spring loaded so that it is urged in a counter-clockwise direction. Secured in the shaft 196 is a metallic strip 197, the end 198 of which is curved and is adapted to partially embrace the rod 88 when it is in its extreme position to the left end of the slot 87, as seen in Figure 17. This strip cams against the rod 88 as it is moved back and forth in the slot 87 and only in the extreme left position of the rod 88 does the portion 198 partially embrace the rod.

In Figure 17, the article ejector slide is not shown withdrawn. However, when the rod 88 is in the position shown in solid lines, the article ejector slide 28 is withdrawn so that the article 199 may drop down on the ledge 41 between the bar 88 and the end 54 of the article ejector 28. Now, when the article ejector is again moved inwardly, the article 199, between the end 54 and the plate member 197, rolls along the surface of the ledge 41 to the right, and while this is occurring, the plate member is traversing an arc indicated by dotted lines, so that as soon as the curved end 198 of the plate member is far enough from the right edge of the ledge 41 for the article to pass therebetween, it rolls out and downwardly into the article delivery opening 26.

It is understood that the above detailed description of the present invention is intended to disclose an embodiment thereof to those skilled in the art, but that the invention is not to be construed as limited in its application to the details of construction and arrangement of parts illustrated in the accompanying drawings, since the invention is capable of being practiced and carried out in various ways without departing

from the spirit of the invention. The language used in the specification relating to the operation and function of the elements of the invention, is employed for purposes of description and not of limitation, and it is not intended to limit the scope of the following claims beyond the requirements of the prior art.

What is claimed is:

1. In a vending machine, a series of main article columns, a series of article ejectors, one for each of said columns and each ejector carrying an interposer having an entering wedge portion, a lock out chain comprised of two series of aligned elongated elements of rectangular cross-section supported on a common plane, the elements of each series having abutting ends in alignment with a different one of said interposers, said entering wedge portion being adapted to enter between the abutting ends in alignment therewith, said chain having a fixed barrier at one end thereof contacted by the first end elements in each series, the elements in both said series being substantially equal in length with the exception of the two elements on the ends opposite said first ends, each of the elements of the upper series having its edge, adjacent to the corner facing away from said barrier and nearest to the entering wedge portion of a co-operating interposer, notched so that they cannot be held against movement and thereby cheat the machine, a coin mechanism, a coin return mechanism having a movable member, a lever pivotally mounted on the second end element of said last mentioned series and comprising a lock normally locking said lock out chain, cam means on said lever extending into said coin mechanism and adapted to cam against a coin positioned therein and thereby to unlock said chain, and means carried by the second end element in the other of said series adapted to cooperate with and lock said movable member of the coin return as long as said upper series is unlocked by the presence of a coin in said coin control.

2. In a vending machine having a plurality of article columns, a series of article ejectors for ejecting articles therefrom, each of said ejectors carrying an interposer, a lock out chain disposed across the paths of said interposers, said lock out chain being comprised of two series of movable elements of rectangular cross section, one resting on top of the other and both disposed in a longitudinal guideway and having abutting ends in alignment with said interposers, a fixed barrier at one end of said lock out chain so that the increase in length of the chain due to the entering of any interposer is in a direction away from said barrier, thereby causing the elements on the opposite end of said chain from said barrier to move in a path parallel to said guideway, and coin control means mounted on the end of said machine opposite the end where said barrier is located, said coin control means including means to cam a lever pivoted on a free end element of one of said series over a coin therein to unlock said mechanism, said coin control means also including a coin return bar having an opening therein in alignment with a free end element of the other series in said lock out chain and so positioned relative to said last element that the latter enters said opening and remains in it during a vending operation, and non-wedging means formed in the elements of the series which is normally locked for prevent-

ing the holding of that series against resetting by a vendee.

3. In a vending machine having article columns, article ejectors cooperating therewith and an interposer moved by each injector, a lock out chain comprised of two series of superimposed elongated movable elements of rectangular cross-section disposed in a longitudinal guideway, each element of the upper series being positioned atop its corresponding element in the lower series, the elements at one end of said chain abutting a fixed barrier and the elements at the other end of said chain being movable by any interposer entering said chain, one of said last mentioned elements in the lower series carrying means to lock the coin return bar of a coin control carried in said machine and the other of said elements in the upper series carrying lever means adapted to cam against a coin positioned in said coin control for unlocking the machine and initiating a vending operation, each of the elements in the upper of said series having its edge, adjacent to the corner facing away from said fixed barrier and nearest to a cooperating interposer, notched so that an operator cannot prevent the lock out chains from resetting and thereby defraud the machine.

4. In a vending machine, a lock out chain comprised of a first series of rectangular movable elements disposed in a trough like depression in said machine and having abutting ends in alignment with interposers, each of which is carried on a different one of the article ejectors of a series of article ejectors in said machine, a fixed barrier at one end of said series, a second series of rectangular movable elements disposed upon said first series and cooperating with said barrier, the elements in said second series being like in length to those in said first series with the exception of the free end elements in each series, each interposer having an entering wedge portion in alignment with the abutting ends of the adjacent elements so that it may enter between the abutting ends of two adjacent elements in each series conjointly, a coin return mechanism, a coin control mechanism, means cooperating with the free end element in said first series for locking said coin return mechanism against operation when said entering wedge portion had conjointly entered in between the adjacent elements of both series, and means on the free end element of the second series normally locked but adapted to cooperate with a coin in said coin control mechanism to release itself and permit said conjoint action, each of the elements in said second series with the exception of the free end element having its edge, adjacent to the corner facing away from said barrier and nearest to the entering wedge portion of a co-operating interposer, notched to prevent a person from defrauding the machine, the free end element of said second series which is normally locked being of the same series in which the other elements are notched as aforesaid.

KUNO EDGAR HAMANN.
